UNITED STATES PATENT OFFICE.

SIMON A. CUMMINS, OF VIENNA, NEW JERSEY.

IMPROVEMENT IN REAPING-MACHINES.

Specification forming part of Letters Patent No. 40,463, dated November 3, 1863.

To all whom it may concern:

Be it known that I, SIMON A. CUMMINS, of the town of Vienna, county of Warren, in the State of New Jersey, have invented an improvement in reaping-machines which I believe to be both new and useful; and I hereby declare that the following is a full and exact description thereof, reference being had to the accompanying drawings, and to the letters of reference marked thereon.

The nature of my invention consists in an apparatus which receives the grain when cut by the reaper, and delivers it at the side of the reaper for being formed into swaths or sheaves, acting automatically by its connection with the reaper, and performing the functions heretofore commonly accomplished by the tail-board and rake.

In the drawings hereto attached, and forming a part of this specification, in all of which the same letters represent the same parts, Figure 1 is a front view of my apparatus as attached to the cutter-board of a reaper. Fig. 2 is an inverted back view of the same. Fig. 3 is a vertical section through line $x x x$ of Figs. 1 and 2. Figs. 4 and 5 are details showing the vibrating toothed beams reversed from the position they occupy in Figs. 1 and 2, and with the outer ends broken off.

To enable others skilled in the art to make and use my invention, I will proceed to describe its construction and operation.

Instead of using a horizontal or nearly-horizontal tail-board to receive the grain or straw as it is cut by the reaper, I raise a table, A, Figs. 1, 2, and 3, slightly inclined backward, as seen in Fig. 3, and resting upon the cutter-board $a a a$ of the reaper. This table is also secured to an end frame-piece, b , and a flat top piece or plate, c . This table A has two or more slots $s s$, Figs. 1 and 3, commencing near the end piece, b , and, as seen very distinctly in Fig. 1, extending to the other end of the table. The ends of the table thus divided by these slots are firmly united together, however, by the slats $d d$. The object of these slots is to allow the passage of the teeth t of the vibrating toothed beams through the table.

As the name indicates, the beams B B have a horizontal vibratory motion imparted to them by the eccentrics of the column C C, and upon their anterior face are provided with the teeth

$t t$, before referred to. They are properly secured to the eccentric pins $p p$ of the column, which consequently gives them not only the aforesaid vibratory motion, but also one back and forth, by which the pins $t t$ are alternately protruded through the slots in the face of the table A, and then withdrawn. The other end of these beams—that is, the one toward the end frame-piece, b —may be made to have similar motions in various ways. It is evident it must have the horizontal motion imparted by the eccentric column C. To give it the to-and-fro or advancing or receding motion imparted to the other end by the eccentric pin p , I find the simplest plan to be to make an oblique slot in the end, as shown at o in Fig. 5. The slot plays upon a fixed pin shown at n in Fig. 1 and dotted in section in place in the oblique slot o . It is obvious that as a beam B is moved toward or from the end frame-piece, b , in which the pin n is firmly fixed by the action of the eccentric column C, the pin will throw forward or withdraw its end of the beam very nearly as the other end will be by the eccentric pin p , thus giving a like motion to the beam in its entire length. Another arrangement for the same purpose is shown in Fig. 4, where n is the section of the pin; q , a ratchet or dog secured to the inside of the end frame-piece, b , and falling at the proper time into the catch or notch q' , and r a spring attached to the anterior or toothed face of the bar B and pressing upon the posterior surface of the table. In this arrangement the beam B has a curved surface at the end, upon which the pin n acts to advance the pins of the beam through the slot s , compressing the spring r , and finally, when the beam has reached its greatest prolongation or vibration toward the end piece, b , the ratchet or dog q falls into the catch q' , holding this end of the beam up against the back surface of the table, and consequently keep its pins projecting through the slot, while the beam moves or vibrates in the opposite direction to the end of its stroke or throw. At this moment the ratchet or dog q , having passed beyond the limits of the catch q' , is freed, allowing the spring r to act and throw the end of the beam back against the pin n , and consequently withdrawing the pins $t t$, so that they no longer project beyond the surface of the table A. In both these arrangements one

end of each beam passes through and plays in a mortise in the end piece, *b*, as seen in dotted lines in Fig. 2.

I do not confine myself to any particular number of beams. In the drawings I have represented four, but two would do, and even more than four may be used. When only two are used I should prefer to cause them both to move together in the same direction at the same time; but where four or more are used it is better to cause them to move in sets, as shown in Fig. 3, when it will be seen that while the teeth of the first and third beam from the bottom are protruding through the slots in the table *A* and consequently moving from the end piece, *b*, those of the second and fourth are withdrawn and their beams necessarily moving toward the said end piece, *b*.

The table *A* should be high enough to hold the grain in its full length upon its face. I have represented it as rectangular; but I do not confine myself particularly to this form, as I propose, under certain circumstances, to give what I call the free or delivery edge a sloping form, as shown by the dotted lines *u u*, Fig. 1, in which case I make the lower beams shorter than the upper; and instead of making one continuous slot for the pins of each beam I may make a short slot for each pin, just long enough to give it free play, leaving the space between these several small slots intact. By this means I can strengthen the table even to such an extent as may enable me to dispense with the slats *d d*. As to the length of the table *A*, that will of course be governed by the size or width of the reaper to which my improvement may be applied. In some cases I may make it extend entirely to the delivery end of the beams *B B*, in which case it will be as long or longer than the cutter-bar of the reaper.

Over the end of the vibrating beams *B B*, where they pass through the end frame-piece, *b*, I make a shield, *v*, of wood, sheet-iron, tin, or other suitable material, to prevent these ends of the vibrating beams from being clogged or fouled by the uncut and standing grain.

The column *C*, inclined in a line parallel with the table *A*, is let into the frame of the reaper below and secured above by a trunnion or axis passing up through the top plate, *c*. To give it greater steadiness, if necessary, it may be supported near the middle by the stud *w*, connected at one end with the collar *w'* and at the other firmly affixed to a beam, *w''*, extending back from or forming a part of the reaper itself. It will also be seen by reference to Fig. 3, which shows these several parts, that the column is nearly divided or cut through in several places, leaving only a pin, *p p*, to connect the several parts of the column together, and that these pins are eccentric—that is, removed as far as possible from the proper axis of the column itself. It is around these pins that one end of the beams *B B* is secured by a large collar or otherwise, and it is the motion of these pins that imparts a vibratory motion to

each beam and the to-and-fro or advancing and withdrawing action to one end, the other end having this motion produced as already described. The motion of this column *C* is obtained by gearing into or being otherwise connected with the moving parts of the reaper, and this connection may be made at bottom, top, or any convenient part of the column.

From this description of the several parts of my invention and their arrangement it is presumed its mode of operation can be readily appreciated. The object proposed to be accomplished is substantially the same as that for which the various forms of rakes are now used with the reaping-machine; but by my apparatus the cut grain is delivered in the swath with the utmost regularity, and so quietly that the ripest grain will suffer little loss by shattering. The grain, when cut, instead of falling prostrate upon the ground behind the machine or upon a tail-board, is caught and held in a nearly-vertical position upon the table *A*. The pins *t t* penetrate to a certain distance among the stalks, and by the vibratory motion of the beam to which they are attached advance the grain a distance about equal to the throw of the beam. Here, by the arrangement of the machinery, these teeth are withdrawn until their points do not project above the face of the table. In the meantime another set of teeth attached to another bar rise up, enter among the stalks of the grain, advance it on the distance of the throw of their beam to be again withdrawn, so as to present no impediment to the further movement of the grain, and then the other beam comes forward, projecting again its pins among the stalks, and goes through the same motion and accomplishing the same purpose as before. The grain thus flows, as it were, in a steady stream over the face of the table, standing almost as erect as it grew in the field until it reaches the extreme ends of the beam and the cutter-bar, from whence it is delivered more regularly and quietly than it could have been done by hand, ready to be bound into sheaves or otherwise disposed of, as the case may require. This alternate motion of the beams and pins applies particularly where there are four or more beams in the machine; but where only two beams are used I prefer them to have simultaneous motions, back and forth, to and fro, because otherwise the stalks would be advanced zigzag or with an oscillating motion, which would produce more agitation and shattering of the grain than by the intermittent but otherwise regular movement of the whole mass together.

Having thus fully described the construction and operation of my improvement in reaping-machines, what I claim, and desire to secure therein by Letters Patent of the United States, is—

1. The vibrating toothed beams *B B*, operating as set forth, in combination with the slotted table *A*, constructed and arranged in the manner described.

2. In combination with the slotted table A, constructed and arranged as described, the column C, with its eccentrics $p\ p$, for giving motion to the vibrating toothed beams B B, in the manner and for the purpose set forth.

3. The curved end of the toothed beams B B, moving upon the pin n , in combination with the spring r , ratchet q , and catch q' , or the

equivalent thereof, for giving the required motion to one end of the toothed beams B B, substantially as set forth.

SIMON A. CUMMINS.
